UNITED STATES PATENT OFFICE.

WALTER S. EDMANDS, OF BOSTON, MASSACHUSETTS.

MECHANICAL DRIVE MECHANISM.

Application filed May 27, 1921. Serial No. 473,072.

To all whom it may concern:

Be it known that I, WALTER S. EDMANDS, a citizen of the United States, residing at Boston, county of Suffolk, State of Massachusetts, have invented a certain new and useful Improvement in Mechanical Drive Mechanisms, of which the following is a specification, reference being had therein to the accompanying drawings.

10 The invention relates to an improvement in mechanical drive mechanisms. It is especially intended for application to transmitting movement from a motor to a work shaft. It is more especially intended for application to a power-driven ice cream freezer in combination with a cabinet having a cover, and means whereby when the cover is closed it will automatically start the freezer and when the cover is opened it will 15 automatically stop the operation of the freezer, and is an improvement on the device shown in my prior application filed April 2, 1921, Serial No. 457,880. The drawings show the invention as embodied in 20 an ice cream freezer, but I wish it understood that the claims wherever possible are not to be limited to an ice cream freezer.

25 The invention will be fully understood from the following description when taken in connection with the accompanying drawings, and the novel features thereof will be pointed out and clearly defined in the claims at the close of this specification.

In the drawings, Fig. 1 is a side elevation 35 of a freezer embodying the invention showing the cover closed and the parts in operative position for driving the paddle shaft of the freezer.

Fig. 2 is a front elevation partly broken 40 away of the parts shown in Figure 1.

Fig. 3 is a side elevation showing the cover turned up on its hinge, the hinged top of the cabinet being closed.

Referring now to the drawings, 1 is the 45 tub of an ice cream freezer, which is mounted in a cabinet case 2 having a base 3 and legs 4. The freezer and case are provided with guides to maintain the freezer tub 1 in proper location in the case. Any suitable guides may be provided. As shown in the drawings, one side of the freezer tub is provided with angle irons 6 secured to the sides thereof, each angle iron having a 50 downwardly extending pin 7 which engages 55 a hole in the flange 8 of an annular angle iron secured to the inner periphery of the

case 2. Any suitable guide, however, may be employed, the guide not being a part of the present invention.

The case extends some distance above the 60 top of the tub and is preferably provided with a top 11 hinged at 12 to the top of the case 2, so that it may be swung open as shown in Figure 3. Said hinged top is provided with a spring catch 13, which when 65 said top is closed engages with a projection on the side of the case opposite the hinge to hold the top in closed position.

The paddle shaft 16 of the freezer has suitable gear connection with a crank shaft 70 15 for rotating the paddle shaft. Said gear connection as shown consists of a bevel gear 18 on the paddle shaft which meshes with a bevel gear 19 on the crank shaft 15.

The crank shaft 15 is journalled in suitable 75 bearings 50 having a crank arm 51. Secured to the under side of the hinged top member 11 of the tub is a bracket 52 in which is supported a stud shaft 53 on which is journalled a gear wheel 20. Said gear 80 wheel carries a pin 54 projecting from one face thereof in position so that it is adapted to engage the crank arm 51 when said gear wheel 20 is rotated, thereby actuating the crank to rotate the shaft 15 and thus, 85 through the intermediate mechanism, to rotate the paddle shaft 16.

When the top member 11 is in closed position, as shown in Figures 1 and 2, the gear wheel 20 is in position for the said pin 90 54 to thus actuate the crank. When the top member 11 is turned back on its hinge, as shown in Figure 3, said gear wheel 20 is in position so that the pin 54 will not engage the crank arm 51 and therefore the crank 95 will not be operated. Any suitable mechanism may be provided for actuating the gear wheel 20. The preferred mechanism is an electric motor shown at 22, having a shaft 23 provided with a pinion 24 which 100 meshes with the gear 20 mounted on the stud shaft 53. Said motor being mounted on the hinged member 11 together with the gear wheel 20, the said pinion 24 and gear 20, will always be in mesh with 105 each other whether the hinged member 11 is turned up as shown in Figure 3 or whether it is turned down into closed position, as shown in Figures 1 and 2.

Said motor shaft 23 is driven in the well-known manner of an electric motor. As shown in the drawings, the current of the

motor is introduced by means of an electric cable 25 through an insulated bushing 26 mounted on a metallic bracket 27 secured to the upper side of said hinged top 11; thence the current passes through the wires 28 and 29 to the positive and negative poles of the switch within a box 30 mounted fast on the hinged top 11. The wire 29 leads to the contact member 31 within said box, and the wire 28 is connected with the binding post 32 in the box with which is connected an armature spring 33 carrying a contact member 34.

10 A cover 35 is hinged at 36 to the hinged top 11, said cover 35 having preferably an arched top, as shown, and at parallel sides 37.

15 Secured to the inside of the case 2 within the top is a strike member 38, which is shown as being in the form of an angle iron and which when the top 11 is closed is engaged by the lower end of the contact member 34, and the spring 33 yields to allow the contact member 34 to be forced up into engagement with the contact member 31, thus closing the circuit and starting the motor.

20 25 When the said hinged top 11 is thrown open, the spring 33 opens the contact automatically and stops the motor.

30 The cover 35 is preferably provided with spring catches 39 which engage with projections 40 on the case to hold the cover closed, but the spring catches will yield readily to be disengaged from the said projections 40 whenever it is desired to turn the cover back on its hinge. The hinged top 11 is provided with a handle 41 for convenience in turning it back on its hinge to open it, and in so doing it will also carry back with it the cover 35. If desired the cover 35 can be turned back independently of the hinged

40 45 top 11.

In order to conveniently hold the cover 35 and top 11 in their open position, there is provided a suitable brace. The form of brace shown in the drawings consists of a jointed brace 42, one end of said jointed brace being pivoted to the strike member 38 and the other end being pivoted to the side of the hinged top 11. The said jointed brace 42 will double up in jack-knife fashion, as shown in Figure 1, when the top is closed.

50 55 As previously stated, any suitable motor may be employed to drive the gear wheel 20, the electric motor already described being simply one suitable form of motor for that purpose. Also in the construction shown, the motor is automatically stopped when the hinged top is open. So far as the present invention is concerned, however, a motor 60 might be employed which is continuous in operation even when the hinged member is turned back into the position shown in Figure 3. As soon as the hinged top is turned back so as to raise the gear 20 so that the pin 54 is out of operative relation to the

crank arm 51, the crank shaft and therefore the paddle shaft 16 will stop their rotation whether the gear 20 is still rotating or not. As soon as the cover is closed, bringing the gear 20 into operative relation to the pin 54 70 on the crank arm and the gear 20 rotates far enough for the pin 54 to come into engagement with the crank arm, the crank will be turned and the paddle or stirrer shaft 16 will be rotated. The shaft 16 which has been referred to as the paddle shaft of an ice cream freezer, typifies any work shaft which may be driven by connection with a motor in the manner described and which may be thrown out of action by turning back the hinged 75 member which carries the driving gear 20.

80 What I claim is:—

1. In combination with a work shaft, a crank having driving connection with said work shaft, a frame having a hinged top, a rotary driving wheel, bearings therefor mounted on said hinged top, a motor mounted on said hinged top having driving connection with said driving wheel, said driving wheel having connected therewith a member which when the said hinged top is closed engages the said crank and actuates the work shaft, and which is thrown out of operative relation to the crank when the top is turned up on its hinge. 95

2. In combination with a work shaft, a crank having driving connection with said work shaft, a frame having a hinged top, a rotary gear wheel, bearings therefor mounted on said hinged top, a motor mounted on said hinged top having a shaft carrying a pinion which at all times engages with said gear wheel and rotates the same whenever the motor is in operation, said gear wheel having connected therewith a member which when the said hinged top is closed engages the said crank and actuates the work shaft, and which is thrown out of operative relation to the crank when the top is turned up on its hinge. 110

3. A power-driven ice cream freezer having a stirrer shaft, a crank having driving connection with said stirrer shaft, a case for the freezer having a hinged top, a rotary driving wheel mounted on said hinged top, and means for rotating said driving wheel, said driving wheel having connected therewith a member which when the said hinged top is closed engages the said crank arm and rotates the stirrer shaft, and which is thrown out of operative relation to the crank when the top is turned up on its hinge. 115

4. In combination with a work shaft, a crank having driving connection with said work shaft, a frame having a hinged top, a rotary gear wheel mounted on said hinged top, means for rotating said gear wheel, said gear wheel having a projection thereon which when the said hinged top is closed engages said crank and actuates the crank 120 125 130

and work shaft, and which is thrown out of operative relation to the crank when the top is turned up on its hinge.

5. In combination with a work shaft, a crank having driving connection with said work shaft, a frame having a hinged top, a rotary gear wheel mounted on said hinged top, a motor mounted on said hinged top having a rotary driving shaft, a pinion 10 mounted on said shaft which engages with said gear wheel, said gear wheel having a projection thereon which when the said hinged top is closed engages said crank and actuates the crank and work shaft, and 15 which is thrown out of operative relation to the crank when the top is turned up on its hinge.

6. A power-driven ice cream freezer having a stirrer shaft, a crank having driving 20 connection with said stirrer shaft, a case for the stirrer having a hinged top, a rotary gear wheel, bearings for said gear wheel mounted on said hinged top, and a motor mounted on 25 said hinged top having a pinion which engages at all times with said gear wheel and rotates the same whenever the motor is in

operation, said gear wheel having connected therewith a member which when the said hinged top is closed engages the said crank and actuates the stirrer shaft, and which 30 is thrown out of operative relation to the crank when the top is turned back on its hinge.

7. A power-driven ice cream freezer having a stirrer shaft, a crank having driving 35 connection with said stirrer shaft, a case for the freezer having a hinged top, a rotary driving wheel mounted on said hinged top, a motor mounted on said hinged top having at all times driving connection with 40 said driving wheel whether the hinged top is open or closed, said driving wheel having connected therewith a member which when the said hinged top is closed engages with said crank and actuates the stirrer shaft, and 45 which is thrown out of operative relation to the crank when the top is turned up on its hinge.

In testimony whereof I affix my signature.

WALTER S. EDMANDS.
